UNITED STATES PATENT OFFICE.

WILLIAM M. TYSON, OF LANETT, ALABAMA, ASSIGNOR OF ONE-FOURTH TO R. J. JENNINGS, OF WEST POINT, GEORGIA.

FILLING-END CLEARER.

Application filed March 18, 1927. Serial No. 176,471.

My invention relates to improvements in looms and more particularly to means for withdrawing the trailing end of the old filling from the shuttle when replenishment has been effected.

In looms of the filling replenishing type sometimes called "automatic" looms, the filling is replenished from time to time by substituting for the old filling carrier or bobbin 10 in the shuttle, another containing a supply of filling wound thereon. When the filling is replenished it is the usual practice to part the old filling between the cloth selvage and shuttle. If it be not withdrawn when the 15 filling carrier or bobbin is ejected, it is likely that it will be carried into and produce a defective portion in the cloth.

An important object of my invention is to provide means for withdrawing and holding the filling end.

Another object of my invention is to provide means for preventing clogging of the withdrawing means by the filling ends.

Another object of my invention is the provision of a device of this character which will be automatic and positive in action and which will be simple of construction and operation.

Other objects and advantages of my invention will be apparent during the course of the following description.

In the accompanying drawings which form a part of this specification and wherein like characters of reference denote like or corresponding parts throughout the same.

Figure 1 is a perspective view of the replenishing side portion of a filling replenishing loom having the present invention associated therewith, the loom portions being illustrated in dotted lines and the attachment being shown in its inoperative position.

Figure 2 is a side elevation of my invention at the completion of the filling operation.

Figure 3 is a similar view of the invention in its operative position.

Figure 4 is a detail perspective of one of the positions of the withdrawing member,

Figure 5 is a similar view showing another position thereof, and,

Figures 6 and 7 are details of the swiveling members.

In the drawings, wherein for the purpose of illustration is shown a preferred embodiment

of my invention, the numeral 10 designates the loom frame upon which is mounted the bracket 11 for supporting the hopper or battery 12 containing the filling carriers or bobbins to be transferred. Extending from the bracket 12 is the stud of fixed transfferer shaft 13 on which is mounted the usual transferring mechanism 14 for transferring filling carriers or bobbins 15 from the hopper to the shuttle on call for replenishment of filling.

A lever 16 has one end rigidly secured to the starting rod 17 and extends vertically therefrom on the outside of the loom frame 10. A connecting rod 18 is pivotally attached to the upper end of the lever 16 and connects the same with a crank arm 19 which is rigidly secured to the end of a rock shaft 20. The shaft 20 is journaled in the bearing 21 mounted on the loom frame 10 and in the braces 22 and 23 which are mounted on the shaft 13 the brace 23 being secured to the shaft 13 adjacent its end. A horizontally arranged arm 24 is secured to, or formed integrally with, the brace 23 and surrounds the shaft 20, although not free to turn therewith. An offset arm 25 is adjustably secured to the arm 24 at 26.

A guide block 27 is rotatably secured to the offset arm 25 by means of a stud 28 which passes through an opening in the arm 24 and is retained therein by means of a cotter pin 29 or the like. The block 27 is provided with a bore 30 adapted to slidably receive the withdrawing rod 31 which is provided with a right angular, smooth extension 32.

A lever 33 is connected to the end of the rock shaft 20 and is provided with an enlargement at its upper end having a slot 34 to receive the shaft. The slot 34 permits movement transversely of the shaft 20 but does not permit rotational movement of the shaft with respect to the lever 33 which must turn with the shaft. The lower end of the lever 33 is pivotally connected with the withdrawing member 31 by means of the block 35 having the pin 36 and receiving the end of the withdrawing member 31 to which it is secured by the nuts 37.

A finger 38 is secured to the lay of the loom and is offset forwardly to space the portion of its length opposite to the extension 32 of the withdrawing member 31 from the lay. The finger 38 is preferably formed

with an elongated slot or eye 39 to provide an adjustable connection with the lay. The end of the finger 38 is bent rearwardly and upwardly at 40, and the end of the extension 32 is bent forwardly at 41.

In operation, when the filling replenishing mechanism comes into operation, rotation of the starting rod 17 moves the lever 16 in the direction of the arrow in Figure 1, thereby rotating the rock shaft 20 and moving the lever 33 in the opposite direction from the movement of the lever 16. The lever 33 moves the withdrawing member 31 through an arc to a substantially horizontal advanced position below the finger 38 as shown in Figures 3 and 4. As the quill drops, it falls behind the finger 38 and in advance of the extension 32 of the withdrawing member, as also shown in Figure 3. At the end of the filling replenishing operation, the withdrawing member is returned to its normal position, thereby drawing the filling end 42 forwardly beneath the finger 38, which results in a double loop, as shown in Figures 2 and 5. The finger 38 not only assists in withdrawing the filling end but also acts as a clearer for the withdrawing member, and the extensions 40 and 41 prevent the filling end from moving out of contact with the members 38 and 32.

It will be seen that I have provided a device which is entirely automatic, working in conjunction with the filling replenishing mechanism, which is the only time when loose ends appear to be jerked back into the cloth, and is absolutely positive in operation, as it does not depend upon the actions of springs or the like.

While I have shown and described the preferred embodiment of my invention, it is to be understood that various changes in the size, shape and arrangement of parts may be resorted to without departing from the spirit of my invention or the scope of the subjoined claims.

Having thus described my invention, what I claim and desire to protect by Letters Patent is:

1. The combination with a loom having filling replenishing mechanism, of a rock shaft mounted on said loom, a swiveled guide mounted on the loom, a withdrawing member slidably received in said guide, a crank arm on said rock shaft and pivotally secured to the withdrawing member, and means operable upon rotation of the starting rod of the filling replenishing mechanism to rotate said rock shaft and move said withdrawing member into the path of the falling quill, the swiveled guide causing the end

of the withdrawing member to move in a curved path.

2. The combination with a loom having filling replenishing mechanism, of a rock shaft mounted on said loom, a swiveled guide mounted on the loom, a withdrawing member slidably received in said guide, a crank arm on said rock shaft and pivotally secured to the withdrawing member, means operable upon rotation of the starting rod of the filling replenishing mechanism to rotate said rock shaft and move the withdrawing member into the path of the falling quill, and a finger mounted on the lay of the loom and adapted to cooperate with the withdrawing member to withdraw the filling end. 65 70 75

3. The combination with a loom having filling replenishing mechanism, of a rock shaft mounted on said loom, a swiveled guide mounted on said loom in spaced relation with the rock shaft, a withdrawing member slidably received in said guide, a crank arm on said rock shaft and adapted to turn therewith and provided with a slot to allow transverse movement relative to the rock 80 85 90 shaft, said crank arm being pivotally secured to said withdrawing member, means operable upon rotation of the starting rod of the filling replenishing mechanism to rotate said rock shaft and move the withdrawing member into the path of the falling quill, the swiveled guide causing the end of the withdrawing member to move in a curved path, and a finger mounted on the lay of the loom and adapted to cooperate with the withdrawing member to withdraw the filling end. 95

4. The combination with a loom having filling replenishing mechanism, of a rock shaft mounted for rotation on said loom, means connecting the starting rod of the filling replenishing mechanism with the rock shaft to rotate the same, a swiveled guide mounted on said loom in spaced relation to the rock shaft, a withdrawing member slidably received in said guide and having an angular extension at its end, a crank arm on said rock shaft and adapted to turn therewith, said crank arm being pivotally secured to the withdrawing member, a finger mounted on the lay of the loom and adapted to cooperate with the withdrawing member to withdraw the filling end, and means on the finger and on the angular extension of the withdrawing member to prevent the filling end from becoming disengaged therefrom by transverse movement in either direction. 100 105 110 115

In testimony whereof I affix my signature.

WILLIAM M. TYSON.
